UNITED STATES PATENT OFFICE.

DAVID H. WAGNER, OF DETROIT, MICHIGAN.

VIBRATORY HAIR CUTTER.

Application filed August 3, 1925. Serial No. 47,782.

This invention relates to hair cutters and relates more particularly to electrically actuated hair cutters of the vibratory type, that is to say of the type wherein the movable blade is reciprocated by vibration of the armature of an electro-magnet.

In hair cutters of the described type, it is common to engage the vibratory arm which comprises the armature of the magnet by an 10 adjusting screw for the purpose of accurately regulating the throw of said arm away from the magnet. In the use of such hair cutters, the tendency of such screws to eventually work loose, due to the constant vibratory action 15 of said arm directly transmitted to said screws, is a source of considerable annoyance and lost time.

It is an object of the present invention to provide an adjusting screw for the vibratory arm aforesaid and to maintain a sufficient spring pressure upon said screw to prevent turning thereof, except responsive to positive 20 actuation.

Another object is to provide a vibratory 25 hair cutter having its armature member so connected to the movable blade as to actuate the latter in a true rectilinear motion.

The invention consists further in the employment of an improved casing for a vibratory hair cutter and in the use of an insulating cover for such casing that will protect the operator from shocks.

These and various other objects are attained by the construction hereinafter described and illustrated in the accompanying drawing, wherein:

Fig. 1 is a plan view of the improved hair cutter, the cover of the casing being removed.

Fig. 2 is a longitudinal sectional view of 40 the same, taken upon the line 2-2 of Fig. 1.

Fig. 3 is a cross sectional view of the device, taken upon the line 3-3 of Fig. 1.

In these views, the reference character 1 designates a casing formed preferably of 45 aluminum or some other light metal and having substantially a channel form. To one end of said casing there is rigidly secured by screws 2, a blade 3 which coacts with a reciprocating blade 4, the two said blades 50 having the usual cutting serrations. The blade 3 is slotted lengthwise as indicated at 6 for engagement by a pair of guide pins 7 upon the reciprocating blade.

For electrically actuating the reciprocating 55 blade, there is disposed within the casing 1 a

magnet, comprising an iron core 8 having pole pieces 8^a, 8^b and 8^c, the pole piece 8^c being centrally located as regards the other two pole pieces and being suitably wound as indicated at 9. 9^a indicates conductors leading 60 into the casing 1 for energizing the winding 9.

10 designates an armature coacting with the pole pieces 8^a, 8^b and 8^c, and attached at one of its ends to a heavy U-shaped leaf 65 spring 11, which is mounted fast upon the casing by a bolt 12 and which urges the armature toward the magnet. At its other end the armature carries a substantially U-shaped spring 13 which may have the nature 70 of a sheet metal stamping and which establishes an actuating connection from the armature to the reciprocating blade 4. Preferably this connection is established by engaging the spring 13 in a slot 14 formed in 75 the blade 4 substantially midway between its extremities. The bracket 13 is formed with a pair of spaced fingers 15, which project toward the serrated edge of the blade and bear upon its top face to maintain its proper 80 proximity to the blade 3.

16 designates an adjusting screw threaded 85 into a lug 17 upon the casing 1 and acting through a coiled spring 18 upon the armature 10 to regulate the gap normally intervening between said armature and the magnet. Preferably the inner end of the screw 16 is formed with a socket, as is best seen in Fig. 3, to receive one end of the spring 18. The other end of said spring is held in proper engagement with the armature by means of a pin 19 rigidly carried by the armature and projecting within the spring.

For regulating the proximity of the blades 3 and 4 to each other, a stop 20 bears upon 95 the anchored end of the spring 18 with a pressure regulable by an adjusting screw 21, (see Fig. 3) a spring washer 20^a being interposed between said stop and the head of said screw.

In the operation of the described invention, when the coil 9 is energized by an alternating current the armature 10 will vibrate as is well understood by those familiar with this art. Departing from prior practice the present invention employs a spring 11 such as to urge the armature toward the magnet instead of from the latter, and in order to establish the proper gap between the armature and the deenergized magnet, the spring 110

18 is placed by the adjusting screw 16 under such compression as will overcome the U-spring 11 so far as may be desired. Thus an endwise pressure is exerted upon the adjusting screw 16 both by the leaf spring 11 and the coil spring 18, the former acting through the latter, and this pressure is adequate to quite positively restrain the screw from accidental turning. It is important to note that 10 the screw 16 does not act as a stop limiting the throw of the vibratory arm as is the case with constructions heretofore employed.

The connection between the armature 10 and the movable blade 4 is such as to permit a 15 true rectilinear motion for said blade while allowing the slightly arcuate travel of the armature entailed by its mounting upon the spring 11.

Owing to the spring nature of the connection 20 13, the stress placed upon the moving blade at the limits of its reciprocation is cushioned through yielding of said connection. This absorption of shocks by the member 13 is a precaution against breakage both 25 of said member and of the moving blade.

Accordingly, as the screw 21 is tightened or loosened the spring 11 together with the armature 10 and blade 4 are more or less depressed to regulate the proximity of the 30 blade 4 to the companion blade 3.

The shape of the casing 1 is such as to conveniently fit the hand, and by forming the cover member 22 of insulating material, the 35 possibility of the operator receiving a shock in the event of failure of the insulation of the coil 9 to properly function, is minimized.

What I claim is:

1. In a vibratory hair cutter, the combination with a pair of co-acting blades, one re-

ciprocatory relative to the other and having 40 an opening therein, an electro-magnet, an armature movable to and from said magnet, means acting upon said armature opposing the pull of the magnet, and a member carried 45 by the armature and extending transversely across the movable blade, and having a projection intermediate its ends engaging in said opening of the movable blade, and adapted to bear alternatively against opposite edges of said opening to reciprocate the 50 blade, said member further having an end portion extending beyond said projection and freely bearing upon the movable blade between said opening and the cutting edge of the blade, and holding the two blades in 55 proper proximity.

2. In a vibratory hair cutter, the combination with a pair of co-acting blades, one reciprocating relative to the other and having an opening therein, an electro-magnet, an armature movable to and from said magnet, means acting upon said armature opposing the pull of said magnet, and a U-shaped member carried by said armature and comprising a pair of substantially parallel arms 60 extending transversely across the movable blade and terminally bearing upon said blade at longitudinally spaced points thereof to hold the two blades in proper proximity, said arms being formed with corresponding projections engaging in said opening of the reciprocating blade, engaging opposite edges of said opening for vibrating said blade, said arms being resiliently flexible in the direction of such vibration. 70

In testimony whereof I sign this specification.

DAVID H. WAGNER.
